Primary Examiner — Khawaja Anwar(74) *Attorney, Agent, or Firm* — Woodard, Emhardt, Henry, Reeves & Wagner, LLP(57) **CLAIM**

The ornamental design for a smoke extractor, as shown and described.

DESCRIPTION

FIG. 1 is a front perspective view of a smoke extractor; FIG. 2 is a left perspective view of the smoke extractor; FIG. 3 is a rear perspective view of the smoke extractor; FIG. 4 is a right perspective view of the smoke extractor; FIG. 5 is a top view of the smoke extractor; and, FIG. 6 is a bottom view of the smoke extractor. The broken lines in the drawings show portions of the smoke extractor that form no part of the claimed design.
